US00D730932S

(12) **United States Design Patent**
Kim et al.

(10) **Patent No.:** US D730,932 S
(45) **Date of Patent:** ** Jun. 2, 2015

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventors: **Young-Rim Kim**, Seoul (KR);
Sang-Hyun Park, Seoul (KR)

(73) Assignee: **Samsung Electronics Co., Ltd.,**
Suwon-si (KR)

(**) Term: **14 Years**

(21) Appl. No.: **29/460,188**

(22) Filed: **Jul. 9, 2013**

(30) **Foreign Application Priority Data**

Jan. 9, 2013 (KR) 30-2013-0001397

(57) **CLAIM**

The ornamental design for a display screen or portion thereof with graphical user interface, as shown and described.

DESCRIPTION

FIG. 1 is a front view of a display screen or portion thereof with graphical user interface, showing our new design; and, FIG. 2 is a front view thereof.

The broken lines showing the display screen portion in FIG. 1 and the display device and portions of the graphical user interface in FIG. 2 form no part of the claimed design.

1 Claim, 2 Drawing Sheets

FIG. 1

FIG. 2
